[*] Notice: The portion of the term of this patent subsequent to Jan. 9, 2010, has been disclaimed.

[57] **CLAIM**

The ornamental design for a metallic cranial burr hole cover and bone flap fixation plate, as shown and described.

[**] Term: **14 Years**

DESCRIPTION

[21] Appl. No.: **37,860**

FIG. 1 is a front plan view showing my new design for a metallic cranial burr hole cover and bone flap fixation plate with an attached identification tag and handle shown in broken line outline;

[22] Filed: **Apr. 21, 1995**

FIG. 2 is a right side elevation view of the metallic cranial burr hole cover and bone flap fixation plate, the left side elevation view being identical thereto;

[52] U.S. Cl. **D24/155**

FIG. 3 is a rear plan view of the metallic cranial burr hole cover and bone flap fixation plate; and,

[58] Field of Search D8/71; D15/138, D15/141; D10/61, 64; D24/140, 155; 128/857, 602/17; 604/164, 167; 606/53, 54, 69-72, 60, 80, 87, 96, 97, 98, 130, 184, 185; 623/16; 33/362-366

FIG. 4 is a bottom edge view thereof.

[56] **References Cited**

The broken line outline of the identification tag and handle is for illustrative purposes only and forms no part of the claimed invention.
